UNITED STATES PATENT OFFICE

91,192

DESIGN FOR A CONTAINER

Vera Camille Grote, Chicago, Ill.

Application October 6, 1933. Serial No. 49,414

Term of patent 7 years

To all whom it may concern:

Be it known that I, VERA CAMILLE GROTE, a citizen of the United States, residing at Chicago, in the county of Cook and State of Illinois, have invented a new, original, and ornamental Design for Containers, of which the following is a specification, reference being had to the accompanying drawing, forming part thereof.

opposite to that shown having the same appearance as the side of the container appearing in the drawing.

I claim:

The ornamental design for a container as shown and described.

VERA CAMILLE GROTE.
